UNITED STATES PATENT OFFICE

JOHN D. BUTLER, OF WASHINGTON, DISTRICT OF COLUMBIA

RAZOR BLADE SHARPENER

Application filed April 4, 1930. Serial No. 441,573.

This invention relates to improvements in sharpeners, especially of the type adapted for sharpening safety razor blades, and it consists of the constructions, combinations and arrangements herein described and claimed.

An object of the invention is to provide a sharpener by means of which the blade can be preliminarily cleaned by means of a roll having a felt or similar coating impregnated with finely powdered charcoal, then sharpened by application to a second roll which is covered with a very fine grade of silk.

Another object of the invention is to provide duplicate sets of foregoing rolls which are respectively adapted for operation in different positions of the blade.

A further object of the invention is to associate a presser plate with one of the sets of rolls so that finger pressure need not be relied upon to hold the blade in sharpening contact with either roll.

A still further object of the invention is to mount the sets of rolls upon the walls of a box or similar receptacle, an advantage of the box being to catch the abrasive material sloughing off of one of the rolls so that the possibility of soiling a clean table cover upon which the sharpener may be stood is avoided.

Other objects and advantages will appear in the following specification, reference being had to the accompanying drawing in which

Figure 1 is a perspective view of the improved razor blade sharpener.

Figure 2 is a central longitudinal section thereof, the charcoal shaker being shown in elevation.

Figure 3 is a detail side elevation of the sharpener particularly illustrating the presser plate and the set of rolls with which it coacts.

Figure 4 is a detail cross section taken on the line 4—4 of Figure 3 particularly showing the hinged mount of the presser plate.

A particular purpose of the device is to recondition and sharpen safety razor blades. In the majority of instances persons using safety razors will use a blade until it becomes dull and then throw it away. Sharpening devices for such blades are obtainable

but not many have come into practical use with the result that many thousands of blades are thrown away and the persons discarding them are kept under a continual expense by buying new ones.

The instant device provides not only a very effective sharpener for the purpose but also one which is so attractive in its appearance that many persons seeing it will be induced to acquire it. It comprises a box 1 upon the opposite side walls 2, 3 of which the shafts 4, 5 of sets of rolls 6, 7, and 8, 9 are journaled.

The arrangement of the rolls in sets occurs in the longitudinal direction of the box 1. The set 6, 7 is situated within the box while the set 8, 9 is situated on the outside as plainly shown in Figure 1. The rolls of the first set are larger than those of the second but coacting rolls, that is to say those on the same shaft are of different sizes.

A covering 10 of felt or the like on the rolls 6, 8 is intended to hold a covering of finely powdered charcoal which is applied by a shaker 11 that is conveniently located in one end of the box 1 and held from freely moving about by a recessed retainer plate 12 (Fig. 2). The surface characteristic of the felt covering is such that much of the powdered charcoal will be retained, and the material will even become impregnated with the charcoal to a certain extent as the user continues to apply a razor blade 13 in the manner suggested in Figure 2.

Since the roll 6 is the largest of the pair 6, 8, it follows that the sloughing off of the charcoal during the use of the sharpener may become more noticeable. The box 1, in addition to affording the support for the rolls, then acts as a container for the charcoal thus loosened. The abrasive will collect in a pile 14 (Fig. 2) whence it may be conveniently removed for replacement in the shaker 11 if desired.

A covering 15 of a high grade of silk, satin or the like is applied to the pair 7, 9 of the rolls. After the razor blade 13 has been preliminarily cleaned in the manner suggested in Figure 2 it is moved over into contact with the roll 7 where the sharpening operation is completed. Silk has been found to produce

an extremely sharp edge but it is a requisite of the sharpener that the silk must be of a good quality otherwise the desirable good effect will not be had.

5 Simultaneous turning of the rolls occurs by operation of a crank 16 which is affixed to one of the shafts. These shafts carry pulleys 17, (Fig. 3) at appropriate places, to which a belt 18 is applied. Turning of the crank 16 causes turning of all of the rolls.

10 Coacting with the outer and smaller set of rolls 8, 9 is a presser plate 19 which is hinged to the wall 3 at 20 (Fig. 4). The hinges will be made so that there will be a slight space 15 at 21 between the leaves (Fig. 4). This space provides for a very slight up and down motion of the presser plate under the influence of springs 22 and the insertion of a razor blade 23 in the manner suggested in Figure 1.

20 Vertically aligned pairs of studs 24, 25, respectively carried by the presser plate 19 and by a rigid shelf 26 protruding from the side wall 3 of the box retain and guide the springs. The shelf is situated in the plane of the bottom 25 of the box and extends the area of the bearing of the box so that the sharpener is further stabilized in use. The springs, and consequently the pair of studs are located directly beneath the rolls 8, 9 so that the application of the pressure may be as nearly 30 centered and directly applied as possible.

The operation is readily understood. It is intended to dust the felt coverings of both rolls 6, 8 with finely powdered charcoal or 35 some other light abrasive from the shaker 11. After the charcoal has been worked into the fabric very little of it will loosen in the operation of the sharpener.

40 This is especially true in the instance of the outer roll 8 by virtue of the manner in which the razor blade 23 (Fig. 1) is presented. But the sloughing off of the charcoal will be more noticeable in respect to the inner roll 8, first by virtue of its larger size, second by virtue of the way in which the 45 blade 13 (Fig. 2) is presented. As already stated, the charcoal thus dropped off will collect in a pile 14 (Fig. 2) inside of the box 1 whence it can be removed for reuse in the shaker 11 if desired.

50 Consider first the "broad side" sharpening of the blade 13 (Fig. 2) the user will grasp the blade between the thumb and forefinger of one hand and apply the side of the blade at the edge to the roll 6. The crank 16 is turned in a direction to cause the rolls to rotate as indicated by the arrows in Figure 2. The near end 27 of the box 1 now becomes invaluable as a finger rest. The thumb will be rested upon the edge of the end 27 with the result that the blade 13 can be held in an absolutely correct and steady position.

55 Having completed the preliminary cleaning of the blade on both sides the blade is transferred to the roll 7 where the sharpen-

60 ing operation is completed. The operator will now rest his wrist on the end 27 in such a manner as to completely avoid the surface of the roll 6.

65 Sometimes it becomes necessary to carry out a sharpening action lengthwise of the blade as in the instance of 23 (Fig. 1). The blade is again held between the thumb and forefinger of the hand and applied in the manner designated. As the rolls are turned 70 the blade is gradually guided along the presser plate 19, which by virtue of the function of its springs 22 keeps the blade pressed against the under sides of the rolls 8, 9.

75 Having preliminarily cleaned the blade it is but a short step to slide it along the presser plate into range of the finishing roll 9. Both sides of the blade will be treated in the manner already pointed out.

80 The provision of the pairs of rolls 6, 8 and 7, 9 is not a mere duplication of similar rolls because each of these will play a part in the sharpening operation. It may be found that in sharpening the blade "broad side" as in Figure 2 there may not be that even setting of 85 the microscopic saw teeth which will produce a smooth and painless shave. By running the blade beneath the outer rolls 8, 9 in a direction opposite to that in which it was applied to the rolls 6, 7 there will be a better 90 alignment of the so-called saw teeth with the accomplishment of the effect already brought out.

95 This mode of use of the sharpener is not necessarily adhered to because the operator might turn the device around and work from the end opposite to 27. The crank 16 would then be turned with the right hand while the wrist of the left hand would be rested on the 100 right end of the box (Fig. 2) while arching 105 the hand over the roll 7 for contact of the blade with the roll 6. It is also possible to manipulate the blade 23 (Fig. 1) lengthwise of the presser plate 19 while keeping the box 1 in position so that the right end is in front 110 of the operator. It is optional whether the device shall be used one way or the other, it being readily adaptable to either right or 115 left handed persons.

120 While the construction and arrangement of the improved razor blade sharpener is that of a generally preferred form, obviously modifications and changes may be made without departing from the spirit of the invention or the scope of the claims.

I claim:—

125 1. A razor blade sharpener comprising a box having a rigid shelf extending from one of the side walls in the plane of the bottom thus to extend the bearing surface of the box, a pair of shafts journaled on the side walls of the box, each having a pair of 130 similarly sized rolls arranged in sets respectively inside and outside of the box, means correspondingly surfacing the rolls of each

pair but constituting dissimilar surfacings as to the sets of rolls, means by which one of the shafts is turned and means by which both shafts are turned in unison, a presser plate hinged to one of the side walls in a position above the rigid shelf for limited movement respecting an adjoining set of rolls, and resilient means situated between the shelf and presser plate to urge the latter against said set of rolls.

2. A razor blade sharpener comprising an abrasive roll which is revoluble on a fixed axis, a presser plate between which and the roll a blade is insertible, hinge means along one side of said plate enabling the opposite and free side to swing toward and away from the roll, supporting means for the roll and hinge means, and resilient means expansive between part of the supporting means and the free side of said presser plate tending to keep said plate in substantial parallelism with the axis of the roll.

3. A razor blade sharpener comprising a box having a shelf extending from one of the side walls in the plane of the bottom thus to extend the bearing surface of the box, a pair of shafts journaled on the side walls of the box, each having a pair of dissimilarly sized rolls arranged in sets respectively inside and outside of the box, a surfacing of felt on one pair of the rolls to be impregnated with charcoal for preliminarily cleaning the blade, a surfacing of silk on the other pair of rolls for subsequently sharpening the blade, means by which both of the shafts are turned in unison, a presser plate hinged to one of the side walls in a position above the shelf for limited movement respecting an adjoining set of rolls, and resilient means situated between the shelf and presser plate to urge the latter against said set of rolls.

JOHN D. BUTLER.
